UNITED STATES PATENT OFFICE.

SAMUEL G. LEITCH, OF SOMERVILLE, MASSACHUSETTS.

CARTON.

1,121,737.

Specification of Letters Patent. Patented Dec. 22, 1914.

Application filed September 22, 1913. Serial No. 790,972.

To all whom it may concern:

Be it known that I, SAMUEL G. LEITCH, a resident of Somerville, in the county of Middlesex and State of Massachusetts, have invented certain new and useful Improvements in Cartons, of which the following is a full, clear, and exact description.

The invention relates to cartons and more particularly to that type in which strips of flexible material are employed for securing the edges of a folded and cut blank or sheet together.

It is now common practice to make boxes or cartons of one or more sheets of paper which are folded and cut and to secure the edges of the sheets together by a strip of adhesive cloth or other suitable material.

In practice, it has been found that when a strip of cloth of a single thickness is lapped over the contiguous portions of the sheet, usually where the corner of the box is formed, the strip, particularly when subjected to unusual stresses, is torn or ripped at the joint so that the box will become broken and useless.

The present invention designs to provide an improved carton in which there is a provision for a strip of material which, when applied to the box, will be of several thicknesses to reinforce the joint where the strips usually commence to rip or break away. In this manner, the joints between the sheets and at one corner of the box will be so effectively reinforced that no breaking away will occur at the joint.

The invention consists in the novel features hereinafter set forth and more particularly defined by claims at the conclusion hereof.

In the drawings: Figure 1 is a perspective of a carton embodying the invention. Fig. 2 is a detail perspective showing the manner of folding the connecting strip so it will provide reinforcement at the joint. Fig. 3 is a section taken on line 3—3 of Fig. 1.

A denotes the box formed of paper board, usually formed of a single sheet of material creased or formed at a to form the box corners and cut as at a' to form the end flaps a², one on each side of the box. This type of box is usually folded for convenience in transportation and so that the sides will be parallel to one another.

A strip b of stout fabric having adhesive applied to one side thereof, is lapped over

the end flaps of the sheet forming the box to form a joint between said flaps.

It has been common practice to employ a strip of single thickness which was extended also partly over the end flaps and slitted sufficiently to permit the end flaps to be folded into position. Owing to the great stress at the corner or at the joint where the slit in the connecting strip terminates, the strip when folded, frequently commences to rip so that the connecting strip would be ineffective to form the joint between the contiguous edges of the sheet.

According to the present invention, the strip b is slitted as indicated at b' at each end, and the portions outside of the slits form tabs for securely connecting the end flaps to the reinforcing strip. The intermediate portions between the slits are folded inwardly as at b² and then reverted as at b³ to form three thicknesses of material at the corners where the strip makes the joint or connects the ends of the sheet. The intermediate portions which are folded inwardly are preferably wider at their outer ends so that when they are folded the outer parts thereof will underlie the tabs b⁴. The adhesive on the inner face of the inner thickness will cause that portion of the strip to adhere to the edges of the box and the outer ends will underlie tabs b⁴. The intermediate thickness will adhere to the outer thickness of material and in this manner the three thicknesses of material will be secured together to the box and form a well reinforced joint and a connection between the edges of the sheet forming the box.

The invention thus exemplifies a box in which a reinforced joint or connection is provided which may be provided without material increase in cost of the box, because the reinforcement is formed from portions unnecessary on the flaps. Obviously, the three thicknesses of material at the joints, particularly at the corners where the flaps fold inwardly, will most effectively overcome any breakage at this point where breakage frequently occurs in practice when a single connecting strip is used.

The invention is not to be understood as restricted to the details set forth, since these may be modified within the scope of the appended claims without departing from the spirit and scope of the invention.

Having thus described the invention, what

I claim as new and desire to secure by Letters Patent, is:

1. A box having a joint, and a strip of flexible material extending across the joint and secured to portions of the box adjacent the joint, and having a portion of the strip reverted between the strip and the box to form a reinforcement at the end of the joint and spanning said joint. 40
2. A box having a strip of flexible material lapped around one of its edges and secured to two of its sides forming a joint and having a portion of the strip reverted and spanning said joint to form a reinforcement at the joint between the strip and the box. 45
3. A box having a strip of flexible material lapped around one of its edges and secured to two of its sides forming a joint and having end portions reverted inwardly toward each other and spanning said joint to provide plural thicknesses of the material at the ends of the strip to reinforce the end- portions of the joint. 50
4. A box having a joint, and a strip of flexible material extending across the joint and secured to portions of the box adjacent the joint, said strip having tabs thereon, the intermediate portion of the strip between said tabs being folded to form plural thicknesses of material at the end portions of the joint between the strip and the box. 55
5. A box having flaps, and a strip of flexible material lapped around and secured to the flaps thereon and having tabs thereon secured to the end-flaps of the box, the intermediate portion of the strip between said tabs being folded to form plural thicknesses of material at the end portions of the joint between the strip and the box. 60
6. A box having flaps, and a strip of flexible material, provided on one side with an adhesive coating, lapped around and secured to the flaps thereon by means of said adhesive coating and having tabs thereon secured to the end flaps of the box, the intermediate portion of the strip between said tabs being folded to form plural thicknesses of material at the end-portions of the joint between the strip and the box. 65
7. A box having flaps, and a strip of flexible material lapped around and secured to said flaps and having tabs thereon formed by cutting slits lengthwise of the strip secured to the end flaps of the box, a portion of the strip intermediate said tabs being folded inwardly and intermediate of its length to form plural thicknesses of material at the end-portions of the joint between the strip and the box. 70
